UNITED STATES PATENT OFFICE.

WALTER F. SMITH, OF PHILADELPHIA, PENNSYLVANIA, ASSIGNOR TO THE UNITED ELECTRIC IMPROVEMENT COMPANY, OF GLOUCESTER CITY, NEW JERSEY.

INCANDESCENT-LAMP SOCKET AND KEY.

SPECIFICATION forming part of Letters Patent No. 435,047, dated August 26, 1890.

Application filed August 23, 1889. Serial No. 321,723. (No model.)

To all whom it may concern:

Be it known that I, WALTER F. SMITH, a citizen of the United States, residing at Philadelphia, in the county of Philadelphia and 5 State of Pennsylvania, have invented certain new and useful Improvements in Cut-Out Devices for Incandescent Electric Lamps, of which the following is a specification.

The principal object of my invention is to 10 provide a cut-out device for electric lamps of simple construction, positive in action, and capable of being readily adjusted.

My invention consists of a cut-out device constructed, arranged, and operating in the 15 manner hereinafter particularly described, and pointed out in the claim.

The nature and characteristic features of 20 my invention will be more fully understood taken in connection with the accompanying drawings, forming part hereof, and in which—

Figure 1 is a view partly in elevation and partly in section of an electric-lamp holder or socket with my improved cut-out device applied thereto. Fig. 2 is a similar view of 25 my improved automatic cut-out device, showing portions of an incandescent electric lamp, shunt-circuit, the tube or rod interposed in said circuit, and the means for short-circuiting the dynamo or generator current through 30 the electric lamp.

Referring now to the drawings, x is a circular base-plate of insulating material, as hard rubber, having an annular aperture x' formed therein. The vertical metal support 35 A, secured to the base-plate x , is bifurcated at a^4 and provided with a bearing a^5 and a binding-screw or other terminal device a^6 . The vertical metal support A' , secured to the base-plate x , is provided near its upper extremity with a binding-screw or other terminal device a^7 and with a circular aperture a^8 . The filament y is secured to the vertical supports A and A' in any preferred manner.

E is a lever, provided at one extremity 45 thereof with a finger e , and this lever is pivotally connected to the bifurcated support a^4 . A spring F, interposed between the lever E and the upper extremity of the support A, is in compression and tends to force

the finger e of the lever E into close contact 50 with the vertical support A' .

C is a circular metal plug adapted to fit into the orifice a^6 of the support A' . This metal plug C is provided with a tapped chamber c' to receive the rod or tube G. Onto 55 the threaded-shank of the plug C is mounted or secured an insulating thumb-piece D.

G is a circular tube or rod of high electrical resistance and substantial strength, yet capable of being melted or softened at a low temperature, and provided with a metallic ferrule D' at one end thereof. This rod or tube is secured into the chamber c' of the metallic plug C. In practice good results have been obtained by making this tube or rod G of rubber and graphite; but it may be made of any other preferred insulating material.

K and K' are the two wires or other conductors attached to the terminals a^3 and a^7 , respectively, leading from the source of electrical energy.

I is a threaded thimble secured to the base-plate x , by which the lamp socket or holder is secured to the electrolier or other fixture. The wires K and K' pass through the aperture x' in the base-plate x and through the thimble I.

I' is the housing of the lamp socket or holder, insulated from the thimble I by means of a gasket w .

I^2 is a support for the globe or shade I^3 , which is illustrated in dotted or broken lines in Fig. 1.

I^4 is the glass bulb or vacuum-chamber of any preferred construction.

x^2 and x^3 are insulating-disks supporting the vertical conductors A and A' and the housing I'.

M and M' are spring-actuated clamps, of the usual or any preferred construction, and 90 which serve to retain the glass bulb or vacuum-chamber in position.

N is a switch adapted to short-circuit the filament y , and thereby extinguish the lamp.

The mode of operation of my improved cut-out device is as follows: To adjust the cut-out device the plug C, carrying the rod or tube G, is first introduced through the open-

ing in the vertical arm A' with the ferrule D' in contact with the arm of the lever E until the resistance of the spring F is overcome, when the finger e is raised and the contact between the said finger and the vertical support A' is broken. The lamp is then interposed in the dynamo or generator circuit, in the usual or in any other preferred manner, and the electric current entering the lamp is shunted, and the main-line or generator current is caused to traverse the vertical supports A and A' and the filament y to the source of electric energy at the same time the shunt current traverses the ferrule D' and the tube or rod G to the source of the electric energy. If the filament y is broken or otherwise injured, the intensity of the shunt-circuit will be greatly increased, and the tube or rod G will, by reason of its high electrical resistance, become melted or softened, so that the spring F will cause it to yield or bend and force the finger e into contact with the vertical support A, whereby the electric current is short-circuited through the lever E and the lamp cut out of the dynamo or generator circuit. When the broken or otherwise injured filament has been replaced by a new one, and when the rod or tube G has become cool or hard, the cut-out device may be readjusted so as to include the lamp in the dynamo or generator circuit by simply rotating the plug C, the tube or rod G, and ferrule D' by means of the thumb-piece D. The rotation of the plug C by reason of the bent form of the tube or rod G forces the fer-

rule D' into contact with the lever E to overcome the resistance of the spring F and to raise the finger e, thereby opening the shunt-circuit and including the lamp again in the dynamo or generator circuit. The dynamo or generator current may be short-circuited and the lamp excluded therefrom, either by revolving or withdrawing the plug C; but in either case the spring F will force the finger e into contact with the vertical support A', and thereby close the shunt-circuit, as will be readily understood.

Having thus described the nature and objects of my invention, what I claim as new, and desire to secure by Letters Patent, is—

The combination, in an electric lamp, of two vertical supports, a short-circuiting lever pivotally connected with one of said supports, a spring interposed between said lever and support, a metal plug provided with a threaded shank mounted in the other of said supports, an insulated thumb-piece mounted thereon, a tube or rod melting or softening at a low temperature mounted in said plug, and a metallic ferrule secured to the opposite end of said tube or rod, all arranged in the manner and for the purposes described.

In witness whereof I have hereunto set my signature in the presence of two subscribing witnesses.

WALTER F. SMITH.
